UNITED STATES PATENT OFFICE

HENRY McDONNELL AND JOHN J. MALLEN, OF JACKSONVILLE, ILLINOIS,
ASSIGNORS OF ONE-THIRD TO GEORGE W. CLARK, OF SAME PLACE.

PROCESS OF DECORATING WALLS.

SPECIFICATION forming part of Letters Patent No. 356,230, dated January 18, 1887.

Application filed November 23, 1886. Serial No. 219,681. (No specimens.)

To all whom it may concern:

Be it known that we, HENRY McDONNELL and JOHN J. MALLEN, citizens of the United States, residing at Jacksonville, in the county 5 of Morgan and State of Illinois, have invented certain new and useful Improvements in Process of Decorating Walls and other Surfaces; and we do hereby declare the following to be a full, clear, and exact description of the invention, such as will enable others skilled in the art to which it appertains to make and use the same.

Our invention relates to a process of forming ornamental coverings for walls, ceilings, 15 and other surfaces; and it consists of the several steps which will be more fully herein-after described, and pointed out in the claim.

The object of our invention is to provide an unbroken ornamental covering for walls and 20 ceilings, by the use of paper or other suitable material, by a simple and inexpensive process, easily and readily understood, and cheaply carried out, as it does not require tools or molds of any kind, (although hand-tools may 25 be profitably used at times,) but is or may be performed entirely with the hands of the operator.

We are aware that various processes and 30 ways have been adopted and used for making ornamental covering for walls; but so far as we know such processes have consisted in preparing the covering, whether of paper or other suitable material, in sheets or strips, worked or shaped into configurations, as desired, with 35 molds and other devices, and then attaching such sheets or strips to the walls by some adhesive mixture applied to the reverse side thereof, thus forming joints and breaks in the covering.

40 By our process the covering, whether of large or small surfaces, is so prepared and applied as to be without joint or break, and may be ornamented and beautified as an entirety, without danger of its cracking or separating 45 into blocks or strips. To accomplish this result, we proceed as follows: We first take the paper or other material and separate it into pieces of convenient length and breadth for handling, and then immerse said pieces in 50 water or other liquid and there retain them

until the material becomes thoroughly soaked and of a pulpy consistency. The material is then taken from the liquid and pressed and wrung in the hands until the greater portion of the liquid is removed. It is then spread 55 out in some suitable place and then impregnated or coated with some adhesive mixture, after which it is placed upon the wall or surface desired to be covered, and, while yet soft, worked into different configurations by the 60 use of the hands direct, or by a suitable blunt instrument held in the hands by placing the same against the outer surface of the pieces, and in pushing or otherwise compressing or working the pieces into various fantastic 65 shapes, and thus giving the paper thus applied a regular or irregular corrugated appearance of high or low relief, as may be desired. By this operation the edges of the different pieces as they are applied are so commingled with each other and forced into different forms that the covering presents one continuous mass, being unbroken at any point. By 70 this way the pieces are joined and worked into each other throughout the entire surface 75 to be covered, thus presenting a homogeneous covering without breaks or seams or lines of jointure, and when said joining has been accomplished the paper as applied is allowed to become dry and hard. After the covering 80 has become hardened by drying it is painted, bronzed, or otherwise decorated, so as to present an attractive and artistic appearance.

The decoration of the surface of the covering may be accomplished by any well-known 85 means and by the use of such materials as are applicable to the purpose other than those heretofore mentioned.

In accomplishing the softening of the pieces we have found that by adding certain ingredients—such as alum and a small amount of the oil of cedar—to the liquid used, the material used will be rendered practically fire and vermin proof. This step of our process is not essential to the desired ultimate result, 95 and may or may not be incorporated, as may be desired.

We have further found that by soaking the paper after it has been separated into pieces in a mucilaginous or pasty mixture the same 100

result may be accomplished as in the first instance, without the preliminary step of soaking the pieces in water or other liquids and then applying a coating of paste or adhesive substance, the only effect of this step being to expedite the process. By using the different grades and thicknesses of paper we are enabled to secure large and small configurations or corrugations, as by the use of hard heavy material—such as express paper—a coarse rugged surface is produced. Thus, according to the thickness of the paper used, any desired surface of high or low relief is obtained.

By the result of our process a covering is formed, by the overlapping and commingling of the pieces, which overcomes the defect displayed in wall-papers and like coverings now in general use, in that it prevents the display of cracks or other defects in the wall or ceiling produced by a shrinking or settling of a building.

It is obvious that various changes in the manner and mode of procedure in our process may be made without the least departure from the nature and spirit of our invention.

Having thus described our invention, what we claim as new, and desire to secure by Letters Patent, is—

The process of forming and applying an unbroken covering to walls or ceilings or other surfaces, which consists in separating the paper into pieces of convenient size for handling, reducing said pieces of paper to a pulpy condition by soaking in liquid, impregnating or coating the pulpy substance with an adhesive mixture, and, while it is soft and pliable, spreading it on the walls, ceiling, or other surfaces and working it into configurations, as desired, by the hands or hand-tools, so as to form a continuous and unbroken sheet, and then coloring and beautifying the same, substantially as described.

In testimony whereof we affix our signatures in presence of two witnesses.

HENRY McDONNELL.
JOHN J. MALLEN.
